UNITED STATES PATENT OFFICE

JAMES E. BALES, OF AURORA, ILLINOIS, ASSIGNOR, BY MESNE ASSIGNMENTS, TO
STANDARD OIL COMPANY, OF CHICAGO, ILLINOIS, A CORPORATION OF INDIANA

DESIGN FOR A SERVICE LUBRICATING CART

Application filed May 27, 1932. Serial No. 43,918. Term of patent 7 years.

To all whom it may concern:

Be it known that I, JAMES E. BALES, a citizen of the United States, residing at Aurora, Kane County, Illinois, have invented a new, original, and ornamental Design for Service Lubricating Cart, of which the following is a specification, reference being had to the accompanying drawing, forming part thereof, in which the single figure is a perspective view of a service lubricating cart, showing my new design.

The end and side of my cart opposite, respectively, to the end and side shown in the drawing are similar, respectively, in general appearance to the end and side shown.

I claim:

The ornamental design for a service lubricating cart substantially as shown and described.

JAMES E. BALES.
